UNITED STATES PATENT OFFICE

2,505,694

FULCRUM FOR LOOSE-LEAF BINDERS

John B. Stuereke, Chicago, Ill.

Application January 18, 1946, Serial No. 642,089

4 Claims. (Cl. 129—4)

1

This invention relates to attachments for loose-leaf binders, and more particularly for devices adapted to be supported at the rings of the binder to lift the leaves or sheets around the lower portion of the rings, when the covers of the binder are swung to closed position.

The primary object of the invention is to provide a simple, inexpensive, and rapidly detachable device, to improve the operation of sheet-lifting devices.

The invention is illustrated in a preferred embodiment in the accompanying drawings, in which—

Figure 1 is a fragmentary vertical sectional view of a ring-type binder to which the device of the present invention has been applied; and Fig. 2 is a perspective view of a fulcrum device which is the subject matter of the present invention.

Kengott Patent No. 2,276,987, dated March 17, 1942, shows sheet lifting devices whose operation is improved by the fulcrum device of the present invention.

In the embodiment illustrated, the conventional loose-leaf ring binder is shown having a back 5 to which are hinged cover members 6 and 7. Conventional split rings 8 are generally made up of semi-circular parts, which are secured to a member 9 which permits them to be opened to attach leaves or sheets. While the rings are shown as circular, the invention is adapted to other shapes. The member 9 has a shield plate 10 which covers the ring operating mechanism.

A pair of sheet-lifting attachments are installed on the rings in opposed relation, as shown in Fig. 1, and comprise a longitudinal strip 11 of relatively stiff material, having inwardly extending metal supports 12, which may be secured rigidly in position by means of rivets 13.

The supports 12 are slotted longitudinally and have their inner end portions curled backwardly, to form a rocker-like portion 14, and provide a closed loop.

A detachable bridge member 15 is provided for each pair of opposed rockers 14 and preferably is made of spring metal, having its ends bifurcated by slots 16 adapted to straddle the rings 8. The ends of the bridge member are provided with clasps 17 which may be snapped around the shield member 10. As shown in Fig. 2, the bridge member may be provided with an integrally formed

2

upwardly extending guide flange 18, which has a pair of fingers 19 which are directed backwardly over the bearing portion of the bridge member. These fingers are adapted to impale the open loops of the rockers 14 and serve as loose positioning pivots.

The device is particularly useful in large ring-type loose-leaf binders. To install a fulcrum on each ring, it is merely necessary to position the slots 16 around the base of the rings 8 and snap the clasps into position by pressing downwardly on the center of the fulcrum. The sheet lifting devices may then be placed on the open rings, with their loop portions surrounding the fingers 19. After the leaves or sheets have been placed on the rings, the rings may be closed, and the device is ready for use. It will be seen that when the covers 6 and 7 of the binder are swung together, as indicated by the dotted lines in Fig. 1, the sheet lifters will roll against the fulcrum 15 and against each other and will slide the sheets around the rings 8, without danger of binding or tearing at the holes.

The foregoing detailed description is given for clearness of understanding only, and no unnecessary limitations should be understood therefrom, for some modifications will be obvious to those skilled in the art.

I claim:

- 30 1. A fulcrum for sheet-lifting devices in a loose-leaf ring binder having a shield plate comprising: a detachable arched bridge member of spring metal provided at its ends with securing clasps adapted to snap over the edge portions of a shield plate and hold the central portion of said bridge member spaced from said shield plate, said central portion of the bridge member providing an upwardly presented unobstructed convex bearing surface upon which sheet-lifting devices may roll; and a guide flange extending upwardly from one edge of said bridge member to engage said sheet-lifting devices.
- 35 2. A fulcrum as specified in claim 1, in which the bridge member is made of spring metal and has its clasps bifurcated to snap around the base portion of the ring of the binder.
- 40 3. A fulcrum for sheet-lifting devices in a loose-leaf ring binder having a shield plate comprising: a detachable arched bridge member provided at its ends with securing clasps to engage the edge
- 45 50

portions of a shield plate and hold the central portion of said bridge member spaced from said shield plate; and upwardly and backwardly directed guide fingers on said bridge member to engage sheet-lifting devices.

4. A device as specified in claim 3, in which the guide fingers are integrally formed with the bridge member and are adapted to loosely guide the sheet-lifting devices.

JOHN B. STUERCKE. 10
